SAFETY LIGHT INFORMER

James Lee Roy Hines, Abilene, Tex., assignor of forty-four percent to Harry R. Bridge, Abilene, Tex., and five percent to H. P. Hodge, Jr.

Filed May 16, 1962, Ser. No. 195,060

4 Claims. (Cl. 349—43)

This invention relates to traffic signalling apparatus and more particularly to the visual indication of elapsed time of the illuminated period of a traffic signal lamp.

Numerous devices have been heretofore devised for use in connection with traffic controlling signal lamp assemblies having red and green lamps facing different directions for traffic control purposes. The general objective of all of these devices, is to provide a visual indication to the motorist in an approaching vehicle as to the amount of time remaining before a change in the traffic signal is to occur so that the vehicle operator may be in a better position to exercise judgment as to acceleration, deceleration or stopping of the vehicle. Prior time informing devices therefore involved the use of a plurality of time indicating lamps sequentially illuminated and extinguished to either indicate the elapsed or remaining time of signal lamp illumination by the position of the illuminated time indicating lamp or by the number it illuminates. A separate arrangement of such time indicating lamps was therefore required with respect to each directional side of the traffic signalling assembly and accordingly involved a relatively complex and expensive construction. Furthermore, operation of this plurality of time indicating lamps for each side of the traffic signalling assembly, was necessarily associated with a relatively complex relay control system for effecting the sequential illumination and extinction of the lamps in timed relation to the programmed operation of the traffic controlling lamps of the traffic controlling assembly. In contrast to such prior safety light informers, the device of the present invention involves a single lamp for each viewing side of the traffic signalling assembly and further avoids any complex relay control system, yet achieves the general objective aforementioned of providing the vehicle operator with a visual indication of the time elapsed or time remaining in the illumination period of a traffic signal lamp such as the green lamps illuminated in one direction to indicate permission for vehicle movement.

It is therefore a primary object of the present invention to provide a safety light informing device associated with a traffic signalling lamp assembly which is relatively simple in construction and operation as compared to comparable devices heretofore devised.

Another object of the present invention is to provide a safety light informing device utilizing a plurality of projector devices for projecting time information through an image transmitting window or translucent screen to thereby avoid the use of a plurality of sequentially illuminated and extinguished time indicating lamps and associated relay circuitry.

An additional object of the present invention is to provide a safety light informing device which is associated with a traffic signal lamp assembly, consisting of a light confining housing mounting image transmitting windows through which time information is projected by intermittent control projector devices mounted adjacent each corner within the light confining housing on opposite sides of the image transmitting windows which receive the projected information from centrally mounted mirrors adjustably mounted within the light confining housing.

An additional object of the present invention is to

2

provide a safety light informer having projection lamps associated with each viewing side of the traffic signalling assembly, said projection lamps being alternatively illuminated by the traffic programmer of the traffic signalling assembly, the images being projected by the projecting lamps being changed at timed intervals by indexing control mechanisms energized simultaneously with associated projection lamps.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

15 FIGURE 1 is a front elevational view of a typical traffic controlling signal assembly with the safety light informer of the present invention installed thereon.

16 FIGURE 2 is a top sectional view taken substantially through a plane indicated by section line 2—2 in FIGURE 1.

17 FIGURE 3 is a partial sectional view taken substantially through a plane indicated by section line 3—3 in FIGURE 2.

18 FIGURE 4 is a partial sectional view taken substantially through a plane indicated by section line 4—4 in FIGURE 3.

19 FIGURE 5 is an exemplary circuit diagram illustrating the control system for the safety light informer of the present invention.

20 Referring now to the drawings in detail, it will be observed that the safety light informer constituting the improvement of the present invention, is generally referred to by reference numeral 10 and is shown mounted below a typical traffic controlling signal assembly generally referred to by reference numeral 12 mounted atop a post 14, the traffic controlling assembly having four viewing sides, each viewing side including a traffic signalling red lamp 16 indicating stop, a traffic signalling green lamp 18 indicating go and an optionally energized traffic signalling amber lamp 20 which may be illuminated during the interval between which the lamps 16 and 18 are illuminated. The safety informer device 10 is therefore arranged to provide a visual time indicating signal of the time remaining in the illuminating cycle of the green lamp 18 for example so that the vehicle operator approaching the traffic signalling device 12 may better evaluate the situation in order to determine whether or not to accelerate, decelerate or stop the vehicle. For example, the traffic signalling assembly 12 may involve a fifteen second cycle or period during which the green lamp 18 is illuminated. Accordingly, at the instant the green lamp 18 is illuminated, the device 10 will also be illuminated to provide an image in the form of number 15 indicating that fifteen seconds remain before the green lamp 18 is to be extinguished.

21 The number image appearing through the device 10 will be changed each second until the green lamp 18 is extinguished at which time the illumination of the device 10 on the viewing side thereof associated with the corresponding viewing side of the traffic signalling assembly 12, will be extinguished. It should also be appreciated that the mounting of the safety light informer device 10 may be varied from that illustrated in FIGURE 1 in accordance with other types of traffic controlling signal assembly installations or in accordance with other more desirable relative locations between the safety light informer 10 and the traffic controlling signal assembly 12. The device 10 need only be operatively interconnected with the traffic programmer of the traffic controlling signal assembly 12 as will be hereafter explained and close enough thereto so that the time information provided by the device 10 will

22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70

be correlated to the traffic signals from the traffic controlling signal assembly 12 when viewed by the vehicle operator.

Referring now to FIGURE 2 in particular, it will be observed that the device 10 is housed within a light confining enclosure generally referred to by reference numeral 22 which may be made of any suitable material such as plastic having the requisite strength for supporting the component parts of the device. The enclosure 22 is formed of a plurality of interconnected equally dimensioned side walls 24 respectively corresponding to the viewing sides of the associated traffic controlling signal assembly 12. Thus, as shown in FIGURE 2, the side walls 24 of the enclosure form a square and are interconnected by corner angle brackets 26. It will be appreciated however, that the enclosure 22 may be formed of any number of viewing sides desired to thereby enclose polygons having a different number of sides than that shown. The side walls 24 are interconnected by a bottom base wall 28 to which the corner angle brackets are fastened by means of the fastener assemblies 30 as more clearly seen in FIGURE 3. The enclosure is then finally sealed both for light confining purposes and for protection against weather deterioration of the parts by means of a lid member 32 fastened to the corner angle brackets by means of the fastener assemblies 34.

Each of the side walls 24 of the enclosure is provided with an opening 36 exposing an image display member such as a translucent screen made of frosted glass, referred to by reference numeral 38. The image displaying screen member 38 is mounted on the side wall by means of screen mounting brackets 40 fastened internally to the side walls. An image projecting assembly 42 is mounted adjacent each corner of the enclosure between the base 28 and lid 32. The assemblies 42 are thereby disposed on opposite sides of each screen member 38, one of which assemblies is operative to transmit the number image hereinbefore mentioned, through the screen member 38 with which it is associated. Toward this end, a vertical mounting post member 44 is centrally disposed within the enclosure 22 for mounting a plurality of angularly related reflector holders 46 which respectively mount reflectors or mirrors 48 in such a position relative to an associated assembly 42 as to reflect a projected image of a number through an associated screen member 38. In the present case, four such mirror elements 48 are illustrated disposed perpendicular to adjacent mirror elements but at the proper angle with respect to the optical axis from the projecting assembly 42 as to reflect an image confined to the image displaying screen member 38.

Referring now to FIGURES 3 and 4 in particular, it will be observed that each of the projection assemblies 42 includes a directional timing lamp 50 including a projection type lamp bulb 52 received within a mounting socket member 54 fastened in any suitable manner to a mounting bracket assembly 56 to fixedly position the lamp 50 adjacent to a corner of the enclosure intermediate the bottom wall 28 and the top lid 32. A reflector shield 58 is therefore mounted on one side of the bulb 52 for directing light therefrom radially inwardly of the enclosure 22. Inwardly spaced and laterally offset with respect to the directional lamp 50 is a bearing support 60 fastened to the bottom wall 28 by the fastener assemblies 62 for mounting a bearing assembly 64 adjacent the upper end thereof. Rotatably mounted by the bearing assembly 64, is a driven number disk 66 having located adjacent the peripheral portion thereof, a plurality of spaced number cut-outs 68 by means of which time indicating images are formed. The number disk 66 is made of opaque material and thereby arranged to block the light transmitted from the directional timing lamp 50 except through the cut-out openings of the number cut-outs 68 which are therefore selectively aligned with the light bulb 52 for such purpose by incremental rotation of the disk 66. An indexing mechanism

for each disk is therefore provided including a plurality of axially projecting index pins 70 disposed between the cut-out numbers 68 for engagement by circumferentially spaced drive pins 72 that extend radially from a drive disk 74. The drive disk 74 is connected to the output shaft of an electric motor 76 associated with each of the projection assemblies 42, said motor 76 being fixedly mounted in the enclosure by a supporting bracket assembly 78 fastened to the top lid member 32. It will therefore be apparent that upon energization of the electric motor 76, the drive disk 74 will be operative to intermittently displace the number disks 66 by an incremental amount so as to bring a different number cut-out 68 into optical alignment with the directional timing lamp 50. Light in the form of a number image substantially reduced in size as compared to the size of display screens 38 will therefore be transmitted through the peripheral portion of the number disk 66 when the lamp 50 is energized.

20 The light projected through the light blocking number disk 66, is optically aligned with the focusing lens assembly 80 which is mounted in proper optically aligned position for such purpose by means of a mounting rod 82 which extends inwardly from the supporting bracket assembly 56 on which the lamp 50 is mounted. It will therefore be apparent that the image formed by the light passing through the number disk 66, will be enlarged when focused on the screens 38 by the projection unit 42 within the limited space of the enclosure 22 because 25 of the relationship between the projection unit and the centrally mounted reflector assembly which establish optical paths that do not interfere with each other and which the long enough to produce the desired enlargement on the screen members 38.

30 From the foregoing description, operation of the safety 35 informer device 10 will become apparent. Referring therefore to FIGURE 5, it will be observed that each of the indexing drive motors 76 is connected in parallel with its 40 associated projection lamp 50 so that the indexing drive occurs simultaneously with the energization of an associated projection lamp. It will also be observed, that diagonally opposite projection unit assemblies 42 are interconnected in parallel for alternate energization. Each pair 45 of projection assemblies is therefore energized in accordance with the direction in which the traffic controlling assembly indicates traffic may move. Thus, the respective pairs of projection unit assemblies 42 are alternatively energized from the power source 84 that may be available for operation of the traffic controlling signal assembly 12 upon alternate closing of micro switches 86 and 88 operated through the same traffic programmer system 90 that controls operation of the traffic controlling signal assembly 12. It will be further appreciated from the foregoing description, that other projection arrangements 50 may be resorted to within the contemplation of the present invention, achieving the purposes and objectives in an equivalent or similar manner by forming time indicating symbol images through the use of intermittently displaced light blocking facilities, the intermittent displacement being accomplished by an indexing mechanism energized simultaneously with projection lamps energized under directional control. In this manner, time indicating images of a readily visible size may be displayed by apparatus of unexpectedly simple construction, low cost and 55 reduced size.

The foregoing is considered as illustrative only of the principles of the invention. Further, since numerous modifications and changes will readily occur to those skilled in the art, it is not desired to limit the invention 60 to the exact construction and operation shown and described, and accordingly all suitable modifications and equivalents may be resorted to, failing within the scope of the invention as claimed.

What is claimed as new is as follows:

75 1. In combination with a traffic signalling device having

traffic signalling lamps facing different directions, a time informing system comprising, a light confining enclosure having image display portions facing said different directions adjacent to the traffic signalling lamps, a plurality of time-indicator light sources mounted within said enclosure for emitting light simultaneously with illumination of associated traffic signalling lamps, movable means mounted in said enclosure within the optical paths of the light emitted from said light sources for projecting time indicating images on said display portions of the enclosure, motor means energized simultaneously with said emission of light from the time-indicator light sources and indexing mechanism drivingly connecting said motor means to said movable means for sequentially changing the images projected therefrom in timed relation to the period of illumination of said traffic signalling lamps.

2. In combination with a traffic signalling device having traffic signalling lamps alternatively illuminated and directional time indicator lamp means illuminated simultaneously with one of said traffic signalling lamps, means for indicating elapsed time of illumination of one of said traffic signalling lamps comprising, light confining enclosure means housing said time indicator lamp means and having directional image display portions, movable means mounted in said enclosure means and disposed in the optical paths of light emitted from said time indicator lamp means for selectively transmitting different time indicating images to said display portions, and drive means operative simultaneously with said illumination of the time indicator lamp means for displacement of said movable means by incremental amounts in timed relation to the period of illumination of said traffic signalling lamps, said movable means comprising a plurality of rotatable opaque disks each having peripheral numbered cutout portions substantially smaller than said display portions and selectively aligned with said time indicator lamp means, said drive means comprising motor means energized simultaneously with said time indicator lamp means, and an indexing mechanism drivingly connecting said motor means to each of said rotatable disks.

3. The combination of claim 2, including projection lens means mounted within said enclosure means in said optical paths of light between said movable means and the image display portions for producing an enlargement of the time indicating images formed by the movable blocking means.

4. In combination with a traffic signalling device having traffic signalling lamps alternatively illuminated and directional time indicator lamp means illuminated simultaneously with one of said traffic signalling lamps, means

for indicating elapsed time of illumination of one of said traffic signalling lamps comprising; light confining enclosure means housing said time indicator lamp means and having directional image display portions, movable means mounted in said enclosure means and disposed in the optical paths of light emitted from said time-indicator lamp means for selectively transmitting different time indicating images to said display portions, and drive means responsive to illumination of said time indicator lamp means for displacement of said movable means by incremental amounts in timed relation to the period of illumination of said traffic signalling lamps, projection lens means mounted within said enclosure means in said optical paths of light between said movable means and the image display portions for producing an enlargement of the time indicating images formed by the movable means, and reflector means fixedly mounted in said enclosure means for extending said optical paths of light between said time-indicator lamp means and the image display portions, said enclosure means being polygonal in cross-section and fixedly mounting said time indicator lamp means adjacent each corner on opposite sides of each image display portion, said reflector means comprising a plurality of angularly spaced mirrors mounted centrally within the enclosure means for receiving inwardly directed, non-intersecting light rays from the time indicator lamp means and reflecting said light rays outwardly to said image display portions, said movable means comprising a plurality of rotatable opaque disks each having peripheral number cutout portions substantially smaller than said display portions and selectively aligned with said time indicator lamp means, said drive means comprising motor means energized simultaneously with said time indicator lamp means, and an indexing mechanism drivingly connecting said motor means to each of said rotatable disks.
